THIS IS A LETTER PATENT ON A DESIGN FOR A SHOWER BATH. IT IS A DESIGN FOR A SHOWER BATH WHICH IS ADAPTED TO BE SUSPENDED IN AN ELEVATED POSITION AND WHICH IS PROVIDED WITH A SPRAYING DEVICE FOR SPRAYING WATER UPON THE PERSON TAKING THE SHOWER. THE DESIGN IS A DESIGN FOR A SHOWER BATH WHICH IS ADAPTED TO BE SUSPENDED IN AN ELEVATED POSITION AND WHICH IS PROVIDED WITH A SPRAYING DEVICE FOR SPRAYING WATER UPON THE PERSON TAKING THE SHOWER.

SHOWER BATH

Harold Davidson Robertson, Vancouver, British Columbia, Canada

Application May 10, 1937, Serial No. 141,683
In Canada May 19, 1936

2 Claims. (Cl. 4—151)

My invention relates to improvements in shower baths which are particularly adapted for use in homes and the like where hot water service is inadequate or nonexistent.

6 The objects of the invention are to provide means whereby a shower bath may be taken in any convenient place with a relatively small amount of water; to provide means whereby the water to be used is raised to a suitable height to 10 afford a suitable pressure at the jets and to provide a structure which is portable.

The invention consists essentially of a water container having one or more spraying devices, a suspending means for the container and a receiver 15 for the water used, which receiver is fitted with a demountable screen or lip for leading the water splashed from the body of the person taking the shower bath into the water receiver, as will be more fully described in the following specification 20 and shown in the accompanying drawing in which:—

Fig. 1 is a general view of the shower bath in assembled position.

Fig. 2 is a longitudinal sectional view of the 25 pail suspending means taken on the line 2—2 of Figure 3.

Fig. 3 is a plan view taken on the line 3—3 of Figure 2.

Fig. 4 is a fractionated sectional view of the 30 pail or water container and its connections.

In the drawing like characters of reference indicate corresponding parts in each figure.

The numeral 1 indicates generally a water container or pail having a cylindrical side wall 2, a 35 bottom wall 3 and a supporting rim 4. The pail is fitted with a wire bale 5 by which it is carried and suspended. The bottom wall is provided concentrically with a shower head generally indicated by the numeral 6, which includes a valve 40 seat 7 formed in the bottom wall 3 having a soft rubber ball valve closure 8 fitted upon a stem 9, which in turn connects with a crank shaft 10 having an operating handle 11, shown in dotted line in Figure 4, which handle extends through 45 the side of the shower head to be accessible to the user when standing below it.

Disposed about the periphery of the pail adjacent the bottom wall are two other valves respectively numbered 12 and 13 of a similar type 50 to that above described. The valve 12 is fitted with a rubber hose 14 having at its free end a massage nozzle or spray head 15 of any suitable type, and the valve 13 is fitted with a metallic flexible tube 16, or a suitable universally jointed 55 pipe having a jet 17 which may be set to dis-

charge a spray of water from the pail onto the neck and shoulders of the person using the shower.

The pail 1 is adapted to be carried from the ceiling by a suspending means generally indicated by the numeral 18, which consists of a casing 19 adapted to be secured in an elevated position and having a non-rotating transverse shaft 20 upon which is mounted a drum 21 having an internal volute spring 22 anchored respectively to the drum and the shaft 20 to rotate said drum in one direction. The drum 21 is fitted externally with a tape 23 having a hook 24 at its free end for supporting the pail. Formed upon one edge of the periphery of the drum is a brake drum 25 and a ratchet wheel 26, which is normally engaged by a pawl 27 mounted upon a rock shaft 28. The rock shaft 28 is fitted with a forked arm 29 which carries a brake shoe 30 for engaging the brake drum. A lever 31 is provided for rocking the shaft 28, which is eyed at its free end as at 32 to afford suitable attaching means for a pull cord 33.

The use of the device requires a tub 34 in which the user may stand while taking a shower. I 25 therefore provide said tub with a detachable flaring rim 35 which extends around the major portion of said tub, the ends of said rim being spaced apart to define a gap 36 through which the user may conveniently step into the tub. The 30 gap 36 is adapted to be closed by a cloth apron 37 attached on one side to the end of the rim as at 38 and clipped by any suitable means to the opposite end of said rim as at 39.

In operation, the pail 1 after filling is suspended upon the hook 24 of the tape 23 and is raised with the assistance of the spring 22 to a suitable height; the tub 34 is moved into position and the user steps into it through the gap 36 and closes the apron 37, after which he operates 40 one or more of the spray devices 6, 15 and 17 as he may desire.

After use by pulling the cord 33 sharply the pawl 27 is released from the ratchet wheel 26 and the brake 30 is applied to the drum 25 to prevent the pail from dropping, but by releasing to an appropriate extent the tension on the cord, the tape 23 is allowed to unwind and lower the pail. After the pail is removed, the spring is allowed to rewind the drum 21 and raise the hook 24 50 to a suitable height above the floor.

What I claim as my invention is:

1. A shower bath structure comprising a water container having a gravity spraying device and a suspending means for the container, said sus- 55

pending means consisting of a drum having a flexible member wound thereon adapted to carry the container, spring means for winding the member upon the drum and manually operable means for holding the drum against rotation in one direction.

2. In a shower bath structure having a water container adapted to discharge water by gravity from an elevated position, a suspending means

comprising a fixed shaft, a drum upon the shaft, spring means for rotating the drum in one direction, a flexible member upon the drum for supporting the water container, pawl and ratchet means for holding the drum against rotating to unwind the flexible member and a brake for retarding rotation of the drum.

HAROLD DAVIDSON ROBERTSON.
